UNITED STATES PATENT OFFICE.

HENRI H. COLES, OF PHILADELPHIA, PENNSYLVANIA.

FASTENING FOR RUNNERS OF GRINDING-MILLS.

SPECIFICATION forming part of Letters Patent No. 375,535, dated December 27, 1887.

Application filed February 24, 1887. Serial No. 228,709. (No model.)

To all whom it may concern:

Be it known that I, HENRI H. COLES, a citizen of the United States, residing in the city and county of Philadelphia, State of Pennsylvania, have invented a new and useful Improvement in Fastenings for Runners of Grinding-Mills, which improvement is fully set forth in the following specification and accompanying drawings, in which—

10 Figure 1 represents an end view of a fastening for the runner of a grinding-mill embodying my invention, the shaft being shown in section. Fig. 2 represents a longitudinal section thereof.

15 Similar letters of reference indicate corresponding parts in the two figures.

My invention consists in attaching the runner of a grinding-mill to the shaft thereof in such manner that should the runner be obstructed its fastening slips or yields, whereby injury to the same and connected parts thereof is prevented, as will be hereinafter set forth.

20 Referring to the drawings, A represents the runner of a grinding-mill, and B the shaft thereof.

25 Freely encircling the shaft is a collar, C, having a flange or projecting portion, C', on the side of which is formed, near its outer edge, a circular rim, D, the latter being concentric 30 with the shaft B.

To the collar C, which is shown as corrugated on its outer face, is secured the runner A by a metallic coupling; but for the purposes of this invention said collar may be plain instead of corrugated, and the runner secured thereto in any suitable manner; or the runner may have the rim D directly attached thereto without the collar C.

35 Within the rim D is a collar or sleeve, F, 40 which, by means of a set-screw, G, is connected with the shaft B, whereby said collar rotates with the said shaft. Within the rim D is also a split ring or annulus, E, having two of its ends connected to the collar F, so as

to rotate therewith and with the shaft B. The 45 other ends of the ring are in contact with the tapering plug H, which has its outer end threaded for engagement of a nut, J, by which the degree of expansive action of the plug on the ends of the ring may be adjusted. Inter- 50 posed between the nut J and ring E is a washer, K, for preventing contact of said nut and ring. To the side of the plug H is secured a pin, L, which enters between the ends of the ring E for preventing rotation of the plug. 55

It will be seen that when the plug H is properly tightened against the ends of the ring E the rim D and ring E are firmly connected, whereby the power of the shaft B is imparted to the rim D, and consequently to the runner, 60 the holding action of the split ring being sufficient to rotate the runner during the operation of grinding. Should, however, the runner be obstructed in any manner, whereby its rotation is resisted, the rotation of the shaft B 65 continues, but the split ring slips on the rim D, whereby, while the runner is held by the obstruction, said runner and connected parts are prevented from being injured or fractured.

Having thus described my invention, what 70 I claim as new, and desire to secure by Letters Patent, is—

1. The shaft B, with the runner A loosely fitted thereon, in combination with the collar C, having flange C' and rim D, the collar F, 75 secured to the shaft B, the split sleeve E, and the adjusting tapering plug H, with nut J, substantially as described.

2. The shaft B, in combination with the runner A, having the rim D, the collar F, secured 80 to the shaft B, the split sleeve E, having two of its ends secured to the collar F, the tapering plug H, with screw-threaded end, and pin L, and the nut J, substantially as described.

HENRI H. COLES.
